United States Patent Office.

JEROME B. MELVIN, OF LOWELL, MASSACHUSETTS, ASSIGNOR TO HIMSELF
AND EDWARD B. HOWE, OF SAME PLACE.

Letters Patent No. 63,920, dated April 16, 1867.

IMPROVED VENTILATING BUNG FOR CASKS, &c.

The Schedule referred to in these Letters Patent and making part of the same.

TO ALL WHOM IT MAY CONCERN:

Be it known that I, JEROME B. MELVIN, of Lowell, in the county of Middlesex, and State of Massachusetts; have invented a new and useful Improvement in Bungs or Vent-Plugs, to be used in casks or reservoirs containing liquids, where vent is required; and I do hereby declare the same to be fully described in the following specification, and represented in the accompanying drawings, of which—

Figure 1 is a top view of one of my improved bungs or vent-plugs, after the plug C has been removed.

Figure 2 is the same, with the plug C screwed in.

Figure 3 is a longitudinal section of fig. 1, and has a screw cut the whole length of it, which screws into the cask or reservoir in a hole made to receive it.

Figure 4 is a longitudinal section of fig. 2, having straight sides, and slightly tapering, to drive into a hole in the cask or reservoir.

Figure 5 is a bottom view of the valve B in fig. 1.

Similar letters of reference indicate corresponding parts in all the figures.

My invention consists of a bung or vent-plug, composed of metal, wood, or other suitable material, when the said bung or vent-plug is provided with a valve resting on a sharp-edged annular seat, and a vent-passage communicating from without with a cavity below the valve, also a pressure-passage communicating from within the cask or reservoir with a pressure-chamber above the valve.

In the drawings, A A is the bung or vent-plug, provided with a valve, B, resting on a sharp-edged annular seat, o o; the vent-passage e communicates from without with a cavity, I, made in the substance of the bung or seat, A A, below the valve B; the pressure-passage f communicates from within the cask or reservoir with the pressure-chamber H, above the valve B; the plug C, which is screwed into the top of the bung or vent-plug A A, is concave at the under side, and forms the top of the pressure-chamber H, all as clearly shown in figs. 3 and 4. The valve B, in fig. 4, is a round ball, and rests upon a sharp-edged annular seat, o o, like that in fig. 3; said ball may be made of rubber, or any other elastic substance.

The object of my invention may be easily seen. When the liquid in the cask or reservoir is being drawn out, atmosphere passes in through the vent-passage e into and through the cavity I with sufficient force to lift the valve B, passing the said lifted valve into the pressure-chamber H, and through the pressure-passage f into the cask or reservoir, thus giving free vent to the same and allowing the liquid to run out, and when the liquid ceases to run, the valve falls back on to the seat o o by its own weight. The pressure from within the cask or reservoir acts upon the top of the valve B, through the pressure-passage f, into the pressure-chamber H, thus holding the valve B down on to the sharp-edged annular seat o o, and thereby preventing evaporation, or the escape of any liquid through the said improved bung or vent-plug. When my improved bung or vent-plug is made to screw into the cask or reservoir, a thread is cut the whole length of it, as shown in fig. 3, and by inserting a forked wrench in holes g g, fig. 1, the bung or vent-plug A A is screwed into the cask or reservoir, in a hole made to receive it.

I am aware that a metallic bung, having a knife-like threaded screw to screw into the cask, was patented by T. B. Smith, July 19, 1859, and that a bung having a reservoir for spirit, combined with a system of pipes or passages, and a peculiar valve, was patented by John Keane, September 27, 1859; also that a valve-bung of peculiar construction was patented by Florian Dahis, February 8, 1859; and therefore I wish it to be understood that I disclaim having invented the equivalent in principle or action of either of the said bungs.

But what I do claim as new, and desire to secure by Letters Patent, is—

I claim the combination of the vent-passage e, the cavity I, the valve B, its seat o o, the pressure-chamber H, and pressure-passage f, with the bung or vent-plug A A, the whole arranged substantially as herein set forth and shown, for the purpose specified.

JEROME B. MELVIN.
